ATTORNEY

UNITED STATES PATENT OFFICE

JOHN J. THACHER, OF WETHERSFIELD, CONNECTICUT, ASSIGNOR TO THE FULLER
BRUSH COMPANY, OF HARTFORD, CONNECTICUT, A CORPORATION OF CONNECTICUT

FEED REGULATOR

Application filed February 1, 1926. Serial No. 85,085.

My invention relates to the class of devices that are employed for regulating feed of material, more especially to mechanism for subsequently performing an operation or operations upon such material, it having been found that the apparatus is especially useful in its operation upon bristles or other fibers to promote the feed thereof to mechanism for incorporating such material in brush structures, and an object of my invention, among others, is the production of a feed regulator that shall be simple in construction and particularly efficient in operation to produce a regular, steady and even feed of the material, as from a hopper or receptacle in which said material is contained.

One form of device embodying my invention and in the construction and use of which the objects herein set out, as well as others, may be attained, is illustrated in the accompanying drawings, in which—

Figure 1 is a view in side elevation of a mechanism embodying my improved regulator.

Figure 2 is a similar view, but looking from the right in a direction at right angles to the point of view of Figure 1.

In the operation of feed devices it often happens that the forces tending to promote feed of material are more or less uneven and are not applied to the same degree at all times, wherefore the feed of such material is uneven and irregular. This is especially true in the case of gravity feed devices for the reason that as the material lessens in bulk and reduces in height and weight, the force tending to discharge such material from the lower end of a hopper or similar receptacle is gradually lessened with a tendency to an emission of less and less material as the operation progresses.

My improved apparatus, while not limited in its use in connection with any particular material, or for the supply thereof to mechanism of any particular type, is especially useful in its operation upon bristles or similar fibers that are delivered to brush forming mechanism, which may be of any suitable type.

My improved regulator provides means

for counteracting the lessening of the force that is applied to a mass of material vertically arranged and that is discharged from the bottom of a receptacle, as a hopper, this being accomplished by gradually increasing the artificial force (as a weight or spring) that is applied to the mass as conditions may decrease the effects of the natural force (gravity). My improved regulator may be embodied in the mechanism shown in the drawings herein, which mechanism comprises a base 5 having a column 6 rising therefrom with a feed shaft 7 rotatably mounted therein, a driving pulley 8 being secured to said shaft as a means for rotating it, and a feed disc 9 also being secured to said shaft to receive material, as fibers, bristles, threads or similar material 10, from a hopper or chute 11, and deliver said fibers to a carrier, as belts 12, and by means of which carrier the fibers may be conveyed to mechanism for performing any desired operation upon or in connection with them. In this operation it will be understood that the feed disc 9 is rotated and collects masses of material from the hopper 11 for the delivery of said material separately to the carrier 12.

It is common practice in the manipulation of fibers by means of a chute or hopper, to place a weight upon such mass within the hopper, but in my improved device I effect this result by placing the weight outside of the hopper and by connecting it with a feed plate 13 that is pressed upon the top of the pile of fibers 10. A rod 14 is attached to and rises from the plate 13 through a guide 15 secured to the side of the hopper 11 near its upper end. A flexible tensioning member, as a cord 16, is attached to the upper end of the rod 14 and is wrapped one or more times around a force regulating member, as a sheave 17.

This member 17 is so arranged and formed that as it is moved, as by a weight 18, the point of application of the force by said weight will be changed whereby such force transmitted by the member 17 will be likewise changed. This effect may be accomplished in many different ways. In the structure herein shown the member 17, as a

sheave, is of spiral form as to a portion thereof, with a groove in its outer surface and of spiral form to receive the tensioning member or cord 16. This member, to the outer end of which the weight 18 is secured, passes from said weight around that portion of the sheave 17 of the lesser diameter, and that portion of the member 16 passing from the sheave to the rod 14 extends from that part of the sheave of larger diameter.

From this it will be noted that the force of the weight 18 is transmitted by the cord 16 to the feed plate 13, and as the latter is lowered, as the fibers are removed from the chute, the sheave or force regulating member 17 will be rotated in a contra-clockwise direction in which movement that part of the cord 16 passing from the sheave to the weight 18 will be carried farther and farther from the axial center of said sheave, thereby increasing the leverage through which the weight 18 acts and consequently increasing the force applied by said weight upon the feed plate 13.

It will, therefore, be noted that as the pile of fibers, bristles, threads or similar material, is gradually reduced within the hopper and the weight thereof lessened, this reduction in weight will be compensated for by the effects produced by the weight 18, so that the application of force to the top of the pile of fibers 10 and consequently the pressure of the pile against the edge of the disc 9 will be substantially the same when the mass of such fibers is nearly removed from said chute as it will be when said chute is practically filled with fibers.

The plate 13 is pivotally attached to the rod 14, so that in placing more fibers in the upper end of the hopper the pressure of the plate on the pile in the lower part of the hopper need not be relieved for any great length of time, the mass introduced at the top of the hopper being placed on top of the plate and the latter then being swung to one side out of the open side of the hopper and from underneath the mass on the plate and then quickly raised and replaced on the extreme top of the mass by swinging it into the hopper through the open side thereof.

Wherever the term "fibers" is employed herein to denote the mass of material within the hopper, I intend to be included within said term all material of whatsoever kind that may be employed in the making of brushes, such as bristles, threads, or raw or prepared vegetable fibers, or any other brush material whatsoever.

In accordance with the provisions of the patent statutes I have described the principles of operation of my invention, together with the device which I now consider to represent the best embodiment thereof; but I desire to have it understood that the device shown is only illustrative, and that the invention may

be carried out by other means and applied to uses other than those above set out.

I claim—

1. A feed regulator comprising a receptacle, a pressure applying member for exerting force upon a mass of material within the receptacle, means for removing material from the bottom of said mass, and regulating means connected with said pressure applying member, said regulating means including a suspended weight having a cable connection with said pressure applying member and a variable power transmitting means acting on the cable to cause an increase of force on the pressure applying member as the mass is reduced in said pile.

2. A feed regulator comprising a receptacle, a pressure applying member for exerting force upon a mass of material within the receptacle, means for removing material from said mass at a point opposite to the pressure applying member, means for exerting force upon said pressure applying member comprising a flexible member connected with said pressure applying member, a rotatably mounted regulating member of spiral formation engaged with said flexible member and means for effecting rotation of the regulating member.

3. A feed regulator comprising a receptacle, a plate to rest upon material within said receptacle, a rigid member projecting from said plate, a pivotally mounted regulator having a groove gradually approaching the axial center thereof, a flexible member secured to said rigid member and wrapped around said regulator in said groove, and a weight attached to said flexible member.

JOHN J. THACHER.
